UNITED STATES PATENT OFFICE.

ERASTUS LOVELL METCALF, OF FRANKLIN, MASSACHUSETTS.

DRIVING-CHECK FOR HORSES.

SPECIFICATION forming part of Letters Patent No. 319,006, dated June 2, 1885.

Application filed March 30, 1885. (No model.)

To all whom it may concern:

Be it known that I, ERASTUS LOVELL METCALF, of Franklin, in the county of Norfolk, of the Commonwealth of Massachusetts, have 5 invented a new and useful Improvement in Driving-Checks for Horses; and I do hereby declare the same to be described in the following specification and represented in the accompanying drawings, of which—

10 Figure 1 is a perspective view, Fig. 2 a top view, and Fig. 3 a side elevation, of a driving-check of my invention, the nature of which is defined in the claim hereinafter presented. Fig. 4 shows the check as applied to the head of a horse. Fig. 5 is a rear view of the nose-band, while Fig. 6 is a rear view of the clamp.

15 The said driving-check is to answer the purpose of a bit as used in the mouth of a horse, and is to encompass the head at the nose and 20 above the rear lip of the animal.

25 In the drawings, A denotes a nose-band in the form, in top view, of a semi-ellipse, it terminating at each of its ends in quadrantal enlargements or projections *a b*, one of which 30 projects above and the other below the bow. In each enlargement there is a curved slot, *c*. Extending outwardly from each enlargement is a plate, *d*, shaped as shown, such plate being provided with ears *b' b'*, in which are held the journals of a friction-roller, *e*, the whole forming an eye.

35 In rear of the nose-band A is a clamp, B, of arched form, and having a slot, *h*, in it near each end of it, such slot being to receive one of two looped straps, C, that go through the eyes of the nose-band and at their outer ends through rings *f*, connected to the reins D D by snap-hooks *g g*.

The nose-band, is to go around the nose of a horse, while the bow or clamp is to extend in 40 rear of the head just above the rear lip, the nose-band being suspended by the straps of the head-stalls buckled through the slots of the upper enlargements, *a*. The slots of the 45 lower enlargements, *b*, are to receive the martingale, which is to be buckled into them.

On pulling backward the reins the nose-band and the clamp will be drawn tightly around the nose and rear jaw of the animal, and in general will check his advance or stop 50 him. When one only of the reins is pulled, the clamp at one end will be drawn against the next adjacent eye of the nose-band, whereby the horse will be turned as with a bit when 55 one rein is pulled.

I am aware that a substitute for a bit has been made by using a nose-band and a band under the jaw, the reins passing through loops at the ends of the former and connected to the ends of the latter. The loops in my device are 60 made with the rollers *e*, which insure a free and easy movement of the reins, avoiding danger of their catching in the corners, and tending materially to reduce the wear.

What I claim is—

65 The nose-band A, having the enlargements *a b*, provided with curved slots *c*, and eye consisting of plate *d* and roller *e*, in combination with the clamp B and the looped straps C C, all constructed and arranged as and for the 70 purpose specified.

ERASTUS LOVELL METCALF.
